US00D566134S

(12) **United States Design Patent** (10) **Patent No.:** **US D566,134 S**
Ito et al. (45) **Date of Patent:** **** Apr. 8, 2008**

(54) **CLUTCH LEVER COVER FOR AN AGRICULTURAL MACHINE**

(75) Inventors: **Jun Ito**, Saitama (JP); **Takahiro Suzuki**, Saitama (JP)

(73) Assignee: **Honda Motor Co., Ltd.**, Tokyo (JP)

(**) Term: **14 Years**

(21) Appl. No.: **29/281,194**

(22) Filed: **Jun. 18, 2007**

(30) **Foreign Application Priority Data**

Dec. 19, 2006 (JP) 2006-034799

(51) **LOC (8) Cl.** **15-03**

(52) **U.S. Cl.** **D15/11**

(58) **Field of Classification Search** ..... D15/10-12, D15/17, 21, 22, 28, 31; D12/196; 180/89.1, 180/89.12, 900; 172/42, 43, 250, 256, 508; 56/17.4, 320.1, 320.2, DIG. 20, DIG. 24

(57) **CLAIM**

The ornamental design for, a clutch lever cover for an agricultural machine, as shown and described.

DESCRIPTION

FIG. 1 is a perspective view of a clutch lever cover for an agricultural machine, showing our new design;

FIG. 2 is another perspective view thereof;

FIG. 3 is a front elevation view thereof;

FIG. 4 is a rear elevation view thereof;

FIG. 5 is a top plan view thereof;

FIG. 6 is a right side elevation view thereof; and,

FIG. 7 is a left side elevation view thereof.
